[57] CLAIM

A design for a scrubbing pad, as shown and described.

DESCRIPTION

FIG. 1 is a perspective view of a scrubbing pad showing my new invention;

FIG. 2 is a side view of the scrubbing pad of FIG. 1, with the other side being a mirror image thereof.

FIG. 3 is an end view of the scrubbing pad of FIG. 1, the other end being a mirror image thereof.

FIG. 4 is a plan view of the scrubbing pad of FIG. 1.

FIG. 5 is a bottom view of the scrubbing pad of FIG. 1.

FIG. 6 is a side view of the scrubbing pad of FIG. 6, the other side being a mirror image thereof.

FIG. 7 is a side view of the scrubbing pad of FIG. 6, the other side being a mirror image thereof; and,

FIG. 8 is an end view of the scrubbing pad of FIG. 6, the other end being a mirror image thereof.

FIG. 9 is a plan view of the scrubbing pad of FIG. 6; and,

FIG. 10 is a bottom plan view of the scrubbing pad of FIG. 6.
